TYPOGRAPHICAL MOLD AND SLUG

John W. Eittner, Bellrose, N. Y., assignor to Intertype Corporation, Brooklyn, N. Y., a corporation of New York

Application August 28, 1940, Serial No. 354,510

3 Claims. (Cl. 199—58)

This invention relates to improvements in connection with typographical slug casting machines and is directed more particularly to the problem of shrinkage of character bearing type slugs cast in the molds employed in such machines, for example, as described in Letters Patent No. 436,532 granted September 16, 1890.

The factor of slug shrinkage has always been a source of annoyance and costly difficulties in composing rooms due especially to the resultant variations in the body thickness (point size of the slug body) at different points throughout the length of the cast slugs. It has been established that the slower the rate of cooling of the type metal injected into the slug casting mold, the greater the amount of shrinkage of the type slug. Moreover, it is generally true for different designs of molds that the greater mass of metal constituting the end portions of the molds serves to conduct away or absorb the heat from the ends of a cast slug more rapidly than from the central portions of the slug body. Thus, while the first few slugs cast in a cold mold may measure to size throughout, as soon as the mold becomes relatively hot the central regions of the body of successively cast slugs cool or chill more slowly than the ends with the result that while the slugs are invariably accurate to size toward the ends they are undersize as to thickness along the central portions of the body, the more rapid cooling of the ends resulting in drawing partially solidified metal from the central regions.

Owing to the smaller mass of metal in the body of slugs which are cast to relatively short measures, the factor of shrinkage is usually so small as to be negligible from a practical standpoint. However, with long measure slugs the shrinkage factor is so great as to be quite objectionable and very difficult to contend with. This is especially the case when, according to modern practice, standard 30-em measure slugs are cast in the production of short lines for newspaper columns (12-em for single-column and 18-em for double-column), the machines being equipped with a power driven saw for cutting off the desired 12 or 18-em portions as the 30-em slugs are ejected. Now it will be evident that if the central portion of a 30-em slug body is undersize in thickness, as is always the case due to the factor of shrinkage, the inner end of a short portion which may be sawed off will be thinner than the outer end thereof. Accordingly, when groups of such short slugs are compactly assembled columnwise in the printing form they will naturally run more and more out of parallelism as the

length of the column increases and thus produce printed lines having a fan-like appearance. This non-parallel condition of slugs arising from the shrinkage factor exists in spite of the well known slug trimming operation wherein slender vertically disposed trim ribs spaced usually at two-em intervals are provided on one side of the slug body for the purpose of shaving the slug to a uniform thickness as it is pushed by the usual ejector through a pair of trimming knives. The fact is that the amount of shrinkage within central regions of the slug body is so great that on its untrimmed side only the end portions are shaved by the trimming knife operating on this side of the slug body. 15

The present invention aims to compensate for the factor of shrinkage by a novel expedient which has been discovered only after long and tedious experimentation, the invention in its broadest aspect involving the provision of one or more slots extending part way vertically through the slug body so that the composite cast slug comprises a plurality of constituent and partially segregated mass sections all stably connected together, the effect being to confine shrinkage to several relatively small mass portions of the body of relatively long slugs and thus simulate the condition, as with relatively short cast slugs, of a negligible or at least unobjectionable amount of shrinkage in each portion. 30

Specifically, and to this end, the invention provides a mold having one or more core members in the form of thin fins running fore and aft of the longitudinal casting slot, such members being carried preferably by the cap element of the mold and extending from the rear edge thereof forwardly to a point little more than midway of the depth of the casting slot. According to different embodiments of the invention these fins, which may aptly be termed shrinkage controlling or shrinkage slot producing fins, may project either entirely or only partially across the vertical height of the casting slot, their projection within said slot in either case producing corresponding narrow slots which serve to partially divide up the mass of the slug body into a plurality of constituent and relatively small mass sections each of which, upon cooling, will shrink a uniform and negligible amount. 50

It is important that the aforesaid shrinkage controlling fins be made thin and extend but little more than midway depthwise of the mold, the advantage being that while the slots produced thereby penetrate into the slug body an 55

extent sufficient to effectively divide up that portion of the mass of the body in which the greatest shrinkage strains normally occur, they are so narrow and shallow as not to impair the strength of the slug in a vertical direction to withstand printing pressures. Further, by terminating the slots produced in the slug body well below the character bearing edge thereof the latter is unbroken and thus adapted at all points in its length to support type characters which may be cast thereon in producing lines of different lengths. Moreover, by forming the shrinkage controlling fins as thin as possible (something less than the vertical height of the portion of the mold slot in which the main or body portion proper of a slug is cast has been found adequate for all conditions) the slots produced thereby in the slug body are so narrow as not to intersect or otherwise interfere with the usual vertical trim ribs, and to enable confining the slots to line measure locations that are rarely used, thus assuring square ends on all useful short line character bearing portions which it may be desired to saw off a longer slug.

Should the vertical projection of the fins referred to be such as to form along the casting slot intermediate closed walls of partial fore and aft depth the slots produced thereby in the cast slug will extend entirely through the thickness of the slug body but the divisional mass portions of the body will remain connected together by solid necks of metal above the slots. If on the other hand the vertical projection of the fins is such as to form along the casting slot intermediate but somewhat open walls of partial fore and aft depth, then the slots produced in the slug body will extend only partially through the thickness thereof and the divisional mass portions of the slug body will be connected together by the necks of metal above the slots as before plus a thin web spanning each slot at one side thereof, such web being formed obviously by flow of the injected type metal around the openings left by the shallow or vertically foreshortened fins.

Another feature resulting from the shrinkage controlling fins herein provided is that they serve to firmly retain the slug in place within the casting slot at the time of breakaway of the metal pot, it being well known to those familiar with these machines that especially under slightly "cold" conditions of the mold, the type metal, or the pot mouthpiece, there is a definite tendency for the slug to be drawn backward in the mold to a slight extent during breakaway with the result that the slug is trimmed below proper type-height by the usual back trimming knife.

In the accompanying drawings:

Figure 1 is a front elevation of a well known form of type slug casting mold having the shrinkage slot producing fins of the invention.

Figure 2 is a plan view of the underside or casting face of the upper or cap element of the mold shown in Figure 1.

Figure 3 is a section, taken on the line 3—3, of the mold in Figure 1 and viewed in the direction indicated by the arrows.

Figure 4 shows a type slug cast in the mold in Figure 1, the slug being viewed from the plain side of its body which side is cast against the inner face of the lower or body element of the mold.

Figure 5 is a section, taken on line 5—5 in Figure 4, viewed in the direction of the arrows.

Figure 6 is a front elevation of a well known

form of type slug casting mold differing in design from that of the mold shown in Figure 1, this mold being provided with shrinkage slot producing fins of slightly shallow vertical height according to an alternative embodiment of the invention.

Figure 7 is a plan view of the underside or casting face of the upper or cap element of the mold shown in Figure 6.

Figure 8 is a section, taken on the line 8—8, of the mold in Figure 6 and viewed in the direction indicated by the arrows.

Figure 9 shows a type slug cast in the mold in Figure 6, the slug being viewed from the plain side of its body which side is cast against the inner face of the lower or body element of the mold.

Figure 10 is a section, taken on the line 10—10 in Figure 9, viewed in the direction of the arrows.

Similar parts are designated by the same reference characters in the different figures.

For purposes of illustration the invention is herein shown as applied to type slug casting molds of well known construction and adapted for mounting on a so-called mold carrier or disk which is rotatable by power in order to present a selected mold first in horizontal position for the slug casting operation and thereafter, by rotation of the disk, in vertical position for the slug ejecting operation. At ejecting position the cast slug is pushed forwardly out of the mold slot by the advancing action of a selected ejector blade of the proper size, the slug being moved edgewise thereby through a pair of opposed trimming knives for the purpose of shaving its side faces and thus bringing the body to a uniform thickness throughout its length.

The construction and manner of operation of the aforesaid mold disk, slug ejecting devices and trimming knives are too well known to require detailed explanation here and since these parts in one or another accepted arrangement may be used in connection with the present invention and form no direct part thereof, they are not shown in the drawings. The only exception over usual or standard construction is that the shrinkage controlling fins provided in the mold according to one embodiment of the invention require the provision of corresponding slots in the slug ejector blade in order that the latter may pass through the mold slot. Such slotted ejector blades, however, are also well known in the art in connection with so-called tabular and logo-type producing molds having partitions running the full fore and aft depth of the casting slot to produce a plurality of separate slugs at each cast, all as evidenced by the disclosures, for example, in U. S. Letters Patent Nos. 609,883; 635,305 and 1,082,059.

Referring to Figure 1, the numeral 1 designates the body element of the mold, which element is rigidly secured to the usual mold carrier or disk. The cap element 2 is suitably and firmly secured to the body 1 and by means of interposed liners 3 and 4 of selected thickness the opposed inner faces 5 and 6 of the body and cap elements respectively are held separated from one another a predetermined distance to thus form the side and end walls of a longitudinal slug casting slot 7 of desired height or point size. At the proper time molten metal is injected at the rear of the slot 7 which is closed at the front by a line of matrices presented edgewise to the front of the mold and held in clamped condition endwise of the line by the usual vise jaws 75

in the machine, the characters of the matrices being thus reproduced on the front or character bearing edge of the cast slug.

As heretofore, the wall 5 of the mold slot is plain or smooth while the wall 6 is provided as usual with a number of narrow, shallow and forwardly tapering cross grooves 8 which produce on the corresponding side of the body of the cast slug slim raised trim ribs 9, these ribs being shaved in well known manner by the customary side trimming knives during the slug ejecting operation for the purpose of bringing the slug body to a uniform thickness throughout its length. The grooves 8 may be spaced laterally at arbitrary intervals in different types of molds but for most purposes an even spacing at 2-em intervals is employed. Moreover, the depth of the grooves may differ in different molds but in any case it will be clear that the actual point size or thickness of the cast slug is represented by the measured thickness, after trimming, between the plain side of the body and the trimmed surface of the ribs on the opposite side.

As already pointed out, the body thickness or point size of slugs, especially those of relatively long measures, varies as between the ends and central portions thereof in spite of the aforesaid trimming operation. The fact is that the central regions of the slug body which always cool more slowly than the ends shrink to such extent that the plain side of the body over an area from one-quarter to one-half inch from the ends and, at its highest point, a fraction below the top edge of the slug is somewhat concave. From this it will be evident that the plain side of such a slug will be touched by the corresponding trimming knife only toward the ends thereof and along a line adjacent to the character bearing edge. Thus, in practice, it is a common experience to find one end of a 12-em or an 18-em portion sawed off a 30-em slug thinner than the other end thereof, an objectionable condition of long standing and very difficult to contend with in making up printing forms.

To overcome this condition the present invention provides means in the slug casting mold for dividing or breaking up the injected molten metal and consequently the mass of the slug body into a plurality of constituent and partially segregated short mass portions or sections all of which remain connected together so that a composite slug is cast having substantially the stability and strength of any standard slug of similar size and having an unbroken character bearing edge of full strength and point size throughout the length of the slug. For this purpose the casting slot 7, which in the mold shown in Figure 1 may be assumed to be 30-em in length, is provided over a portion of its depth from the rear face 10 to the front face 11 of the mold with slender fore and aft cores or fins 12 which may be formed integral with the cap element 2 of the mold as herein shown or may be otherwise secured to at least one of the mold elements, the sides of the fins 12 being preferably tapered forwardly as best shown in Figure 2 in order to permit free forward movement of the cast slug during ejection.

It will be observed that while the fins 12 project entirely across the vertical height of the casting slot 7, as clearly shown in Figure 1, they terminate in a fore and aft direction well back of the front face 11 of the cap element 2 and in fact extend little more than midway depthwise of the casting slot 7 as will be seen from Figures 2 and 3, thus forming along the slot intermediate

closed walls of partial fore and aft depth. Moreover, the fins 12 are so thin setwise that they are confined to only a small fraction of the area between the cross grooves 8 in the casting face of the cap element 2, thus avoiding intersection with such grooves and consequent loss of the surface of the trim ribs formed thereby on the cast slug, and are also restricted within the limits of line measures that are rarely used such as 9½-em and 19½-em measures as indicated.

It will now be apparent that the presence of the shrinkage controlling fins 12 within the casting slot of the mold results in the formation in the cast slug 13, Figure 4, of corresponding narrow shrinkage slots 14 extending from the bottom of the slug body upward therethrough to a point little more than midway of the vertical height of the slug, thus leaving a substantial body or neck of metal 15, Figure 5, between their upper ends and the top or character bearing edge 16 of the slug. The slots 14 will be seen to occupy or extend setwise over only a very small part of the slug body between adjacent trim ribs 9, indicated by the dotted lines in Figure 4, and to be confined to and located setwise along the slug body at the rarely used line measure positions mentioned above and indicated by the "em" scale shown in Figure 4.

Thus, the slots 14 partially divide or segregate the mass of the slug body into a plurality of relatively short constituent mass portions each subject to a minimum, uniform and practically negligible amount of shrinkage and all connected together by the solid necks of metal 15 so as to constitute a composite slug of substantially the same stability and strength in a vertical direction as if the slots did not exist. Moreover, the character bearing edge 16 of the cast slug is of full point size throughout and unimpaired in strength vertically so that type characters may be cast thereon and adequately supported thereby at all points. Accordingly a line of any desired length such as the 12-em line of characters 17 represented in Figure 4 may be cast on a slug of longer measure and the short portion of the slug containing such line sawed off for subsequent use alone. Due to the narrowness and the location of the slots 14, it will be apparent that short portions containing 8, 10, 18 or 20-em lines may be sawed off without intersecting the slots 14 so that by a single cutting operation in severing any such short portions the ends adjacent to the cut will be square over their full height, a feature which is not only desirable but also quite necessary for most purposes.

An alternative embodiment of the invention is shown in Figures 6 to 10 inclusive wherein shrinkage controlling fins 18 are provided on the casting face 19 of the cap element 20 of a mold differing in design from that shown in Figure 1. In this instance the fins 18 which are similar to the fins 12 described above differ from the latter in the single respect that they project only partially across the vertical height of the casting slot 21 as clearly indicated in Figures 6 and 8, thus forming along the slot intermediate but somewhat open walls of partial fore and aft depth. In practice it is desirable that the fins project at least half way across the height of the casting slot so that the shrinkage slots 65 produced thereby penetrate an effective depth into the mass of the slug body, that is, deep enough into the thickness of the body to effectively break up the mass thereof. With this arrangement it will be evident that molten metal 75

injected into the casting slot of the mold will flow around the vertically foreshortened fins 18 and produce thin webs 22 of metal spanning each slot 23 formed in the cast slug by the fins, such webs being formed at the side of the slug which is cast against the smooth wall 24 of the body element 25.

The slug 26 cast in the mold shown in Figure 6 is shown in Figures 9 and 10 and this slug will be seen to simulate the slug 13 in Figure 4 except for the presence of the aforesaid thin webs 22 which are clearly discernible in the section of the slug shown in Figure 10. The presence of the webs 22 add of course to the ability of the slug to resist deformation but of greater importance still, such webs definitely assure, upon a single cutting operation, square ends of full vertical height on any short line bearing portion that may be sawed off even though the cut may 20 intersect one of the shrinkage slots 23.

Shrinkage controlling fins projecting entirely or only partially across the vertical height of the casting slot may be used in either of the types of molds shown and, as will be apparent to those skilled in the art, such fins may be used in connection with a wide variety of similar molds including the well known types of recessed molds commonly employed on slug casting machines. In fact, effective compensation for shrinkage has 30 resulted from the provision of shrinkage controlling fins which fall short of the vertical height of the casting slot by an amount sufficient to avoid the necessity of slotting the usual form of slug ejector blade or to require only a slight 35 channeling of the surface of the blade to clear the fins, and fins so foreshortened in projection across the casting slot may indeed be employed if desired.

The principal requirements are that regardless of the particular type of mold in question or the precise shape, size, number, location or vertical projection of the shrinkage slot producing fins provided, the slots penetrate into and thus effectively break up that mass portion of 45 the slug body which is subject to excessive shrinkage into constituent partially segregated but firmly connected mass portions none of which are susceptible to an objectionable amount of shrinkage, and this without weakening the 50 vertical strength of the slug, when used as a whole, to withstand printing pressures, without weakening or reducing the width of the character bearing edge at any point, and without losing the facility to obtain by a single cut square 55 ends on adjacent short slug portions of any desired line measure that may be desired to cut from a longer slug having the shrinkage slots in the body thereof.

As previously stated, the shrinkage slot producing fins described serve also to firmly retain the slug in place in the casting slot of the mold

at the time of breakaway of the usual metal pot. This will be clear by comparing the slug 13 in Figure 4 with the casting face of the mold cap element in Figure 2 against which face the ribbed side of this slug was cast. By superposing the slug on the mold cap shown in Figure 2 it will be seen that the fins 12 definitely anchor the slug against backward movement, that is, movement in a direction away from the front edge 11 of the cap. 10

I claim as my invention:

1. A typographical slug casting mold comprising spaced cap and body elements the innermost opposed longitudinal surfaces of which are substantially parallel and provide walls defining the minimum vertical height of the casting slot, a plurality of fore and aft fins projecting into the space between the aforesaid longitudinal surfaces and having a maximum setwise width materially less than the vertical distance therebetween and said fins having tapered sides extending forwardly from the rear face of the mold to a point of intersection about midway of the fore and aft depth of the casting slot, whereby to provide in the mass portion of the slug body 25 formed by the aforesaid walls shrinkage slots beyond the width and extent of which the slug body is at least the full thickness as determined by the vertical height between said walls. 20

2. A typographical slug casting mold having a 30 casting slot formed by vertical end walls and upper and lower longitudinal walls, the latter walls being substantially parallel continuous surfaces in their respective planes, at least one fore and aft fin projecting vertically across the 35 casting slot between the aforesaid longitudinal walls, said fin having oppositely tapered sides extending from the rear face of the mold forwardly to a point of intersection about midway of the fore and aft depth of the casting slot and 40 having a maximum setwise width materially less than the vertical distance between the longitudinal walls of said slot, whereby to form in said mold a slug of uniform body thickness throughout its length and height with a slot through substantially the lower half only of the body 45 thereof in correspondence with the setwise width and extent forwardly of said fin in the casting slot.

3. A typographical slug casting mold according to claim 2, wherein the upper longitudinal wall of the casting slot is provided with a plurality of shallow fore and aft grooves for forming trim ribs on the corresponding side of the cast slug, and wherein the specified fore and aft 55 fin is located at a fractional line measure position along the casting slot and confined to a fraction of the space between adjacent shallow grooves. 50

JOHN W. BITTNER. 60
